APPARATUS FOR THE CONTROL OF HIGHWAY CROSSING SIGNALS

John M. Pelikan, Greentree Borough, and Henry S. Young, Wilkinsburg, Pa., assignors to The Union Switch & Signal Company, Swissvale, Pa., a corporation of Pennsylvania

Application September 4, 1936, Serial No. 99,424

9 Claims. (Cl. 246—130)

Our invention relates to apparatus for the control of highway crossing signals, and has for an object the provision of novel and improved apparatus controlled by a train approaching the highway crossing for starting the operation of the signal in accordance with the speed of the train.

A feature of our invention is the provision of apparatus of the type here involved wherewith the apparatus is restored and made effective to time a second and following train that approaches the highway crossing prior to the leading train having passed completely over the crossing. A further feature of our invention is the provision of apparatus of the type here contemplated wherewith unnecessary operation of the apparatus by trains moving against the normal direction of traffic is avoided. Other objects and advantages of our invention will appear as the specification progresses.

Apparatus and circuits for the control of highway crossing signals similar to applicants' apparatus and circuits are disclosed in the co-pending application for United States Letters Patent, Serial No. 53,759, filed December 10, 1935, by J. K. Mickley for Apparatus for the control of highway crossing signals, and of which copending application the instant application is an improvement.

We will describe two forms of apparatus embodying our invention, and will then point out the novel features thereof in claims.

In the accompanying drawings, Fig. 1 is a diagrammatic view of one form of apparatus embodying our invention, and Fig. 2 is a diagrammatic view of a second form of apparatus which also embodies the invention. Fig. 3 is a vertical sectional view showing one type of a rail microphone which may be used as the track instrument in the apparatus of Figs. 1 and 2.

In each of the different views, like reference characters designate similar parts.

Referring to Fig. 1, the reference characters $1a$ and $1b$ designate the track rails of a stretch of railway track over which traffic normally moves in the direction indicated by an arrow, and which rails are intersected at grade by a highway H . A highway crossing signal S is located adjacent the intersection and, as here shown, is an audible signal in the form of an electric bell. It will be understood, of course, that our invention is not limited to this one form of signal and other forms such as a flashing light signal, a color light signal, gates, or barriers may be used if desired.

The track rails $1a$ and $1b$ are divided by the

usual insulated rail joints to form two track sections $X—Y$ and $Y—Z$, which sections are traversed in the order named by a train approaching the highway crossing when moving in the normal direction of traffic. Each track section is provided with a track circuit comprising a battery 2 connected across the rails at one end of the section and a track relay TR plus a prefix corresponding to the location connected across the rails at the other end of the section. The section $Y—Z$ is preferably arranged for its exit end Z to be adjacent the highway crossing and its entrance end Y to be far enough away from the crossing to provide a predetermined minimum warning period of operation of the signal S prior to the arrival of a train at the intersection when the train is operated at a speed not exceeding a certain prescribed speed, operation of the signal being initiated when the train reaches the location Y . Track section $X—Y$ may be of any convenient length and in practicing our invention, the location X will usually be an automatic block signal location. In order to more easily understand the apparatus embodying our invention, we shall assume that the location Y is located in the rear of the highway H a distance sufficient to provide 20 seconds operation of the signal S prior to the arrival of a train at the intersection when the train is moving at 45 miles per hour, the operation of the signal being as stated above initiated as the train enters the section $Y—Z$. Hence, under these conditions, the section $Y—Z$ is substantially 1320 feet in length, since a train travelling at a speed of 45 miles per hour will advance approximately 1320 feet in 20 seconds.

The operation of the signal S is accomplished through the medium of an interlocking relay IR . The relay IR may be any one of several well-known types of interlocking relays, and it is deemed sufficient for the present description to point out that the circuit controlling contact fingers 30 and 31 are operated by the winding 5 of the relay, contact fingers 32 and 33 are operated by the winding 6 , and these contact fingers are provided with an interlocking mechanism not shown whereby their movements are interlocked. The arrangement is such that contact finger 30 makes engagement with a full down contact 34 only when winding 5 is deenergized while winding 6 is energized, but with winding 5 energized or when deenergized subsequent to deenergizing of winding 6 , contact finger 30 is held out of engagement with contact 34 . Contact finger 31 is held in engagement with front contact 35 when winding 5 is energized and is released to break

engagement therefrom when winding 5 is deenergized while winding 6 is energized. In the case winding 6 is deenergized while winding 5 is energized, the interlocking mechanism is operated 5 and contact finger 31 is held in engagement with contact 35 even though winding 5 is subsequently deenergized.

Two track instruments M1 and M2 are located spaced apart along the track section X-Y. 10 These track instruments are preferably alike and may be any one of several types, and, as here shown, are rail microphones of a type described and claimed in the United States Letters Patent No. 1,834,077, granted December 1, 1931, to A. J. 15 Sorensen. Referring particularly to Fig. 3, the microphone M1 is attached to the rail by means of a clamp 4 which is secured to the base of the rail by a lug 3 and a bolt 15. The microphone comprises an insulating housing 14 attached to the clamp 4 by a screw 16, and which housing contains two spaced vertically disposed metal electrodes E and E1. The space between these electrodes is at least partly filled with carbon granules 13. The parts are so proportioned that 20 under the conditions that the microphone M1 is not vibrated, the resistance between the electrodes E and E1 through the carbon granules is relatively low, but that when the microphone is vibrated and the carbon granules are agitated, the resistance between the two electrodes is increased several times its normal value. As stated 25 above, the microphone M2 is preferably similar in construction to the microphone M1.

Again looking at Fig. 1, the microphone M2 is attached to the rail, as indicated by a dotted line, at a location V, and which location is a distance from the highway H sufficient to provide a predetermined period of operation of the signal S prior to the arrival of a train at the intersection 30 when the train is operating at the maximum speed for all trains, operation of the signal being initiated when the train reaches location V. Thus, if 90 miles per hour be assumed as the maximum speed for all trains and the desired operating period for the signal S is 20 seconds, the location V is substantially 2640 feet to the rear of the highway H and approximately 1320 feet to the rear of location Y. The microphone M1 is attached to the rail at a location U to the rear of 35 location V. The distance between locations U and V is, in effect, a timing track section for determining the speed of a train and in accordance with which speed the time of starting the operation of the highway crossing signal is determined. 40 This timing track section may be of any convenient length and is made to agree with the desired operating period of a time measuring means to be referred to hereinafter, and also in accordance with the speed of trains at this locality. In 45 order to agree with the train speeds we have assumed hereinbefore and to agree with a preferred form of time measuring means about to be described, we shall assume that the timing track section U-V is 270 feet in length. That is, the 50 two rail microphones M1 and M2 are located 270 feet apart which is the distance traveled by a train in 4 seconds when operating at a speed slightly above 45 miles per hour. It is apparent that such timing track section does not require any 55 subdivision of the track circuits as established for the usual wayside signal system, since these track instruments may readily be applied to the track rail at any point.

A repeater relay is associated with each of the 55 rail microphones M1 and M2, a relay R1 being as-

sociated with microphone M1 and a relay R2 being associated with the microphone M2. Each of these relays is provided with a pick-up circuit and with a stick circuit. The pick-up circuit for relay R1 comprises three branch paths over any one of which current may be supplied to the winding of the relay and the relay energized. The first branch path extends from the B terminal of any convenient source of current such as a battery not shown, back contact 8 of track relay ZTR, line wire 9, winding of relay R1, and to the C terminal of the same source of current. The second branch path includes battery terminal B, back contact 18 of relay R2, wire 11 to wire 9, and thence the same as traced for the first branch path. The third branch path includes battery terminal B, front contact 12 of a relay DR to be referred to later, wire 17, wire 9, and as previously traced. The stick circuit for relay R1 includes battery terminal B, its own front contact 18, wire 18, electrode E of microphone M1 (see Fig. 3), the carbon granules 13 of the microphone, electrode E1, wires 20 and 9, winding of relay R1, and to the opposite terminal C of the current source. The pick-up circuit for relay R2 has two branch paths, one of which passes from battery terminal B over back contact 21 of track relay ZTR, line wire 22, winding of relay R2, and to the C battery terminal. The second branch path includes front contact 52 of relay DR, to be referred to later. The stick circuit for relay R2 includes battery terminal B, its own front contact 23, wire 24, the electrodes and carbon granules of microphone M2, wires 25 and 22, winding of the relay, and to the C battery terminal. Hence relays R1 and R2 are retained energized normally by virtue of their respective stick circuit which in each case includes the associated rail microphone.

That unnecessary operation of the apparatus 40 may be avoided when a train is moving against the normal direction of traffic, a directional relay DR is provided and is controlled over a pick-up circuit comprising battery terminal B, contact 31-35 of relay IR, back contact 26 of relay 45 ZTR, line wire 27, winding of relay DR, and to the C battery terminal. Relay DR may be retained energized over a stick circuit which includes back contact 28 of track relay XTR and its own front contact 36 as will be readily understood by an inspection of Fig. 1.

The apparatus includes a time measuring means operative to determine the time consumed by a train in traveling the timing section U-V and which means permits operation of the signal 55 S when a train traveling this timing section at a speed above a predetermined speed, here assumed to be 45 miles per hour, reaches the location V, and delays the starting of the operation of the signal S until the train reaches the location Y when the train speed is less than 45 miles per hour. As here shown, the time measuring means, indicated as a whole by the reference character TM, consists of a slow pick-up slow release relay TE, and an associated stick relay TES which is slightly slow releasing in character. The arrangement is such that a complete cycle of operation of relay TE is employed in timing a train over the timing section U-V. On the assumption the timing section U-V is 270 feet in length and the train speeds are as assumed hereinbefore, the pick-up period of relay TE is 2 seconds and its release period is 2 seconds, thereby providing a complete cycle of operation of 4 70 75

seconds. Relay TE is normally deenergized and is provided with an energizing circuit which passes from battery terminal B over back contact 37 of relay R1, back contact 38 of relay TES, winding of relay TE, and to the C battery terminal. The associated stick relay TES is initially energized over a front contact 49 of relay TE, and may be retained energized by a stick circuit which includes battery terminal B, back contact 41 of relay TE, wire 39, two branch paths in parallel to wire 29, one of which paths includes back contact 42 of relay R1, and the other of which includes back contact 53 of relay R2, thence over front contact 43 of relay TES, and winding of the relay to the C battery terminal.

The control circuit for energizing the winding 5 of relay IR includes three branch paths. The first path is normally closed and includes battery terminal B, front contact 44 of relay R2, wire 45, front contact 46 of relay ZTR, winding 5, and to the C battery terminal. A second path is normally open and includes front contact 49 of relay TES, back contact 50 of relay TE, wire 51 to the wire 45, and thence as traced for the first path. The third path is also normally open and includes a front contact 47 of the directional relay DR, wires 10 and 51 to wire 45 and as previously traced.

Normally, that is, when both track sections X-Y and Y-Z are unoccupied and their respective track relays XTR and ZTR are picked up, the repeater relays R1 and R2 are retained energized by their respective stick circuits and the winding 5 is held energized over the circuit including front contact 44 of relay R2 and front contact 46 of relay ZTR.

In describing the operation of the apparatus in Fig. 1, we shall first assume a train traveling at the maximum speed of 90 miles per hour approaches the highway crossing from the left. This train upon entering section X-Y shunts track relay XTR and that relay is released to close back contact 28. This operation performs no useful function at this time and need not be considered further for this train. When the head end of the train reaches location U, the microphone M1 is vibrated and relay R1 is released due to the increase in the resistance of the microphone and to the resultant decrease in the energization of the relay. The release of relay R1 and the closing of its back contact 37 completes the energizing circuit for relay TE and that relay is energized to initiate its cycle of operation. The train traveling at 90 miles per hour advances from location U to location V in about 1½ seconds and microphone M2 is vibrated and relay R2 is released. Release of relay R2 to close its back contact 40 supplies current to relay R1 and that relay is picked up to open back contact 37 and thereby stop operation of relay TE. Since the pick-up period for relay TE is 2 seconds, further operation of the time measuring means is not effected after the arrival of the train at location V. Release of relay R2 to open front contact 44 upon the arrival of the train at location V causes winding 5 of relay IR to become deenergized since its other branch paths are now open, with the result that contact 30-34 is closed and signal S is set into operation to warn highway users. It follows that signal S is set into operation upon the train reaching location V and 20 seconds operation of the signal prior to the arrival of the train at the intersection is effected since location V is substantially 2640 feet from the highway. When the head end of

the train enters section Y-Z and shunts track relay ZTR that relay is released to close its back contacts 8 and 21. The closing of back contact 21 supplies current to relay R2 and that relay is picked up, and the closing of back contact 8 supplies current to relay R1 and that relay is retained energized after relay R2 is picked up even though the rear of the train might not yet have passed the location U, and microphone M1 is still vibrated. Consequently, the relays R1 10 and R2 are restored to their normal positions in response to the head end of the train entering the track section Y-Z. Operation of the signal S is continued while the train is in section Y-Z since the circuit of winding 5 is open at front contact 46 of relay ZTR. When the train proceeds over the crossing and vacates section Y-Z, the relay ZTR is picked up and winding 5 is re-energized to stop operation of the signal S.

We shall next assume a train approaches the 20 highway crossing from the left traveling at a speed slightly less than 45 miles per hour. This train, upon entering section X-Y, shunts relay XTR the same as before. Furthermore, when the head end of the train reaches location U, relay R1 is 25 released and an operation of the relay TE is initiated the same as described for the first train. This train traveling at a speed slightly less than 45 miles per hour consumes something over 4 seconds in passing from location U to location V. At 30 the expiration of 2 seconds from the time the train reaches location U, relay TE picks up and closes its front contact 46 which, in turn, picks up relay TES. With relay TES picked up, the energizing circuit for relay TE is open at back contact 38 and relay TE is deenergized and releases at the expiration of its 2 seconds slow release period. Relay TE upon releasing to close its back contact 41 completes the stick circuit for relay TES and that relay is retained energized as 40 long as either relay R1 or R2 is down. Hence, when the head end of the train reaches location V and relay R2 is released to open front contact 44 interposed in the control circuit for winding 5, winding 5 is retained energized over the branch 45 path which includes front contact 49 of relay TES and back contact 50 of relay TE. Consequently, operation of the signal S is delayed until the train enters section Y-Z and shunts track relay ZTR to open the control circuit for winding 5 50 at the front contact 46 of that relay. Since location Y is substantially 1320 feet from the highway crossing substantially 20 seconds operation of signal S prior to the arrival of the train at the intersection is effected for this train operating at 55 about 45 miles per hour. When the head end of this train enters section Y-Z and shunted relay ZTR, the repeater relays R1 and R2 are restored to their normal positions the same as described for the first train. When relay R2 is picked up, 60 the stick circuit for relay TES is opened and the time measuring means is restored to its normal position. It is clear that for all train speeds between 45 and 90 miles per hour the signal S is set into operation upon arrival of the train at the 65 location V, but that for train speeds below 45 miles the time measuring means completes its cycle of operation and operation of the signal is delayed until the train enters the section Y-Z. Furthermore, in all cases, the relays R1 and R2 as well as 70 the time measuring means are restored to their normal positions in response to the head end of the train entering the track section Y-Z.

Under the traffic conditions, where a second train enters section X-Y before the first train 75

has completely passed out of that section or out of the section Y—Z, the relays R₁ and R₂ are in a position to control the time measuring means and to time the second train through the timing section, if the first train advances and vacates section Y—Z prior to the head end of the second train reaching the location of microphone M₁. Hence, the apparatus will govern the operation of the highway crossing signal in accordance with the speed of the second train the same as for the first train.

In case a train operating against the normal direction of traffic, that is, moving from the right to left in Fig. 1, enters section Y—Z and shunts track relay ZTR, the closing of back contact 26 of relay ZTR completes the pick-up circuit for the directional relay DR since the contact 31—35 of relay IR is now held closed by the interlocking feature of that relay, it being understood that winding 6 is controlled by trains approaching the highway from the right. Relay DR thus picked up, it will be retained energized over its stick circuit which includes back contact 28 of relay XTR until this train recedes from the crossing and vacates section X—Y. With directional relay DR picked up, the repeater relays R₁ and R₂ are held energized while the train operates past the associated rail microphone, relay R₁ being supplied with current over front contact 42 of relay DR, and relay R₂ being supplied with current over front contact 52 of relay DR. Hence, unnecessary operation of the time measuring means by a train operating over track sections Y—Z and X—Y against the normal direction of traffic is avoided.

It is to be noted that relay DR when picked up completes at its front contact 47 the third branch path for supplying current to the winding 5 of relay IR as soon as the train moving from right to left vacates section Y—Z. This releases the interlocking feature of relay IR. Then if this train should reverse direction and again approach the highway the signal S will be operated as soon as the train reenters section Y—Z.

In Fig. 2, the track layout and apparatus is the same as in Fig. 1 except a third track instrument M₃ and an associated relay R₃ are added. The track instrument M₃ is preferably the same as the track instruments M₁ and M₂, and, as here shown, is a rail microphone which is operatively connected with a track rail at a location W along section Y—Z and which location is preferably near the entrance of the track section Y—Z. Relay R₃ is controlled over a circuit extending from battery terminal B, back contact 54 of track relay XTR, line wire 55, back contact 56 of directional relay DR, electrodes and carbon granules of microphone M₃, winding of relay R₃, and to the C terminal of the current source. In this form of the invention, the pick-up circuits for relays R₁ and R₂ as well as their stick circuits are normally closed. These pick-up circuits include back contacts 57 and 58 of relay R₃, respectively, as will be readily understood by an inspection of Fig. 2.

It is believed that the apparatus of Fig. 2 may best be understood by describing the operation thereof, and to that end we shall first assume a train traveling less than 45 miles per hour approaches the highway crossing from the left. This train, upon entering track section X—Y, shunts track relay XTR which releases and closes back contact 54 with the result the relay R₃ is picked up leaving the two relays R₁ and R₂ held energized over their stick circuits. When the head end of the train reaches location U and

causes release of relay R₁ due to vibration of microphone M₁, current is supplied to the relay TE of the time measuring means and that relay is energized to start its cycle of operation. This energizing circuit may be traced from the B battery terminal over front contact 59 of relay R₂, back contact 60 of relay R₁, wire 61, back contact 62 of relay TES, winding of relay TE, and to the C battery terminal. At the end of 2 seconds, relay TE picks up and completes at its front contact 63 a pick-up circuit for relay TES which circuit is the same as the energizing circuit just traced for relay TE up to wire 61, thence over front contact 63 of relay TE, winding of relay TES, and to the battery terminal C. With relay TES once picked up, it completes a stick circuit at its front contact 64 and shunts around the front contact 63 of relay TE. Relay TES on picking up, also opens the energizing circuit for relay TE at back contact 62, and relay TE is de-energized and releases at the end of 2 seconds its slow release period. When relay TE releases to close its back contact 65, current is supplied to the winding of relay R₂ over a circuit including back contact 66 of relay TE and front contact 67 of relay TES. Since this train requires something over 4 seconds in advancing through the timing section U—V, the above described cycle of operation of relays TE and TES is completed prior to the arrival of the train at location V with the result that relay R₂ is held energized subsequent to the microphone M₂ being vibrated by the passing train. With relay R₂ thus retained energized, the control circuit for winding 5 of relay IR and which circuit includes front contact 68 of relay R₂ and front contact 69 of relay ZTR is held closed until the train advances to location Y and enters section Y—Z to shunt track relay ZTR. Hence, operation of the signal S is not effected for this train moving less than 45 miles per hour until the train occupies section Y—Z. When the train arrives at location W and causes vibration of microphone M₃, the relay R₃ is deenergized and releases to complete the pick-up circuits for relays R₁ and R₂ and relay R₁ is picked up, relay R₂ having been retained energized by the time measuring means. Relay R₁, on picking up, opens its back contact 60 and deenergizes the relay TES and that relay is restored to its normal deenergized position. Consequently, the relays R₁ and R₂ as well as the time measuring means are restored to their normal positions in response to the head end of the train reaching the location W which, as stated hereinbefore, is preferably close to the entrance of section Y—Z.

We shall next assume a train moving at a speed higher than 45 miles per hour approaches the highway crossing from the left. This train shunts track relay XTR and causes relay R₃ to be picked up the same as before. Furthermore, when the train reaches location U and vibrates microphone M₁ the relay R₁ is released to close the energizing circuit for relay TE and start the operating cycle of the time measuring means. This train, however, advances and reaches location V is less than 4 seconds, and hence causes the release of relay R₂ before relays TE and TES have had time to complete their full operating cycle. Relay R₂, upon releasing, opens the control circuit for winding 5 at front contact 70 69 and hence operation of the signal S is started when the train reaches location V. Again, relay R₃ is released when the head end of the train reaches location W and the relays R₁ and R₂ are restored to their normal energized positions, 75

operation of signal S being continued since relay ZTR is now shunted. It is to be seen, therefore, that relays R1 and R2 and the time measuring means are in all cases reset and ready to time a second and following train which might enter the track section X—Y before the leading train has vacated that section or section Y—Z.

A train moving from the right to left in Fig. 2, and entering section Y—Z, shunts the track relay ZTR and that relay upon releasing closes at its back contact 68 the pick-up circuit for the directional relay DR which picks up and is then retained energized over a stick circuit that includes back contact 54 of relay XTR and its own front contact 69 until such time as the train recedes from the crossing and vacates section X—Y. With directional relay DR picked up, the relay R3 is not energized when the relay XTR is released, and hence the relays R1 and R2 are retained energized during the time this train receding from the crossing moves past the track instruments M1 and M2, and unnecessary operation of the time measuring means is avoided. When this train moving from the right to the left vacates section Y—Z relay ZTR picks up to energize winding 5 of relay IR and release the interlocking feature of that relay. If this train should now reverse its direction and approach the highway the winding 5 is deenergized and the signal is operated when the train enters section Y—Z and shunt relay ZTR.

Although we have herein shown and described only two forms of apparatus embodying our invention, it is understood that various changes and modifications may be made therein within the scope of the appended claims without departing from the spirit and scope of our invention.

Having thus described our invention, what we claim is:

1. In combination, a stretch of railway track intersected by a highway and formed into a track section to one side of the intersection, a track circuit for said section including a track relay, a highway crossing signal located at the intersection, two track instruments capable of operation by a train and located one at each of two selected locations which a train passes prior to entering said track section in approaching the intersection, a normally energized first relay governed by the track instrument nearer the section and effective to start operation of the signal when deenergized in response to the head end of a train reaching the location of that instrument, a normally deenergized time measuring means effective when energized a predetermined time interval to render said first relay ineffective to start operation of the signal, a normally energized second relay governed by the track instrument more remote from the section and effective to energize the time measuring means when deenergized in response to the head end of a train reaching the location of that instrument, other means including a front contact of the track relay to operate the signal, and means controlled by a train to restore said first and second relays as well as the time measuring means to their normal positions in response to the head end of a train entering said track section.
2. In combination, a stretch of railway track intersected by a highway and formed into a track section to one side of the intersection, a track circuit for said section including a track relay, a highway crossing signal located at the intersection, two track instruments capable of

operation by a train and located one at each of two selected locations which a train passes prior to entering said track section in approaching the intersection, a normally energized first relay governed by the track instrument nearer the section and effective to start operation of the signal when deenergized in response to the head end of a train reaching the location of that instrument, a normally deenergized time measuring means effective when energized a predetermined time interval to render said first relay ineffective to start operation of the signal, a normally energized second relay governed by the track instrument more remote from the section and effective to energize the time measuring means when deenergized in response to the head end of a train reaching the location of that instrument, other means including a front contact of the track relay to operate the signal, and means including a back contact of said track relay effective to restore said first and second relays as well as the time measuring means to their normal positions.

3. In combination, a stretch of railway track intersected by a highway and formed into a track section to one side of the intersection, a track circuit for said section including a track relay, a highway crossing signal located at the intersection, two track instruments attached to a track rail one at each of two selected locations which a train passes prior to entering said track section in approaching the intersection, a normally energized first relay governed by the track instrument nearer the section and effective to start operation of the signal when deenergized in response to the head end of a train reaching the location of that instrument, a normally deenergized time measuring means effective when energized a predetermined time interval to render said first relay ineffective to start operation of the signal, a normally energized second relay governed by the track instrument more remote from the section and effective to energize the time measuring means when deenergized in response to the head end of a train reaching the location of that instrument, other means including a front contact of the track relay to operate the signal, means including a back contact of said first relay and a back contact of the track relay in parallel to energize said second relay, and other means including a back contact of the track relay to energize said first relay.

4. In combination, a stretch of railway track intersected by a highway and formed into a track section to one side of the intersection, a track circuit for said section including a track relay, a highway crossing signal located at the intersection, two track instruments attached to a track rail one at each of two selected locations which a train passes prior to entering said track section in approaching the intersection, a normally energized first relay governed by the track instrument nearer the section and effective to start operation of the signal when deenergized in response to the head end of a train reaching the location of that instrument, a normally deenergized time measuring means effective when energized a predetermined time interval to render said first relay ineffective to start operation of the signal, a normally energized second relay governed by the track instrument more remote from the section and effective to energize the time measuring means when deenergized in response to the head end of a train reaching the location of that instrument, other means including a front contact of the track relay to restore said first and second relays as well as the time measuring means to their normal positions in response to the head end of a train entering said track section.

- lay to operate the signal, a third track instrument attached to a track rail along said track section, a third relay governed by said third track instrument and effective to restore said 5 first and second relays as well as the time measuring means when operated in response to the head end of a train reaching the location of the third instrument.
5. In combination, a stretch of railway track intersected by a highway and formed into a track section to one side of the intersection, a track circuit for said section including a track relay, a highway crossing signal located at the intersection, two track instruments attached to a track 10 rail one at each of two selected locations which a train passes prior to entering said track section in approaching the intersection, a normally energized first relay governed by the track instrument nearer the entrance of said section 15 and effective to start operation of the signal when deenergized in response to the head end of a train reaching the location of that instrument, a normally deenergized time measuring means effective when energized a predetermined time 20 interval to render said first relay ineffective to operate the signal, a normally energized second relay governed by the track instrument more remote from the entrance of the section and effective to energize the time measuring means 25 when deenergized in response to the head end of a train reaching the location of that instrument, other means including a front contact of the track relay to operate the signal, a third track instrument attached to a track rail substantially 30 at the entrance of the track section, a third relay, an energizing circuit for the third relay including a contact actuated of the third instrument and which contact is opened when a train 35 passes the location of the third instrument, means including a back contact of said third relay to energize said first relay, and other means including another back contact of said third relay to energize said second relay.
6. In combination, a stretch of railway track intersected by a highway and formed into a track section on one side of the intersection, a highway crossing signal located at the intersection, a track circuit for the section including a track relay, a track instrument attached to a rail at 40 a location which a train passes prior to entering the section in approaching the intersection, a time measuring means effective at times to govern the operation of said signal, a first relay governed by the track instrument to control said time measuring means in response to a train 45 passing the location of the instrument, a signal controlling interlocking relay including a winding energized over a front contact of the track relay, a directional relay, a pick-up circuit for the directional relay including a front contact operated by said winding and a back contact of the track relay, a stick circuit for the directional relay including a back contact of another track relay which a train shunts subsequent to passing through said track section in receding from the intersection, and means including a front contact of the directional relay to render said first relay ineffective to operate the time measuring means when the receding train passes the 50 location of said instrument.
7. In combination, a stretch of railway track intersected by a highway and formed into a track section on one side of the intersection, a highway

crossing signal located at the intersection, a track circuit for the section including a track relay, a track instrument attached to a rail at a location which a train passes prior to entering the section in approaching the intersection, a control relay governed by the track instrument and effective to cause the signal to be operated in response to a train passing the location of said instrument, a directional relay, a pick-up circuit for said directional relay including a back contact of said track relay and another contact controlled by a train and closed when a train enters the section at the end adjacent the intersection, a stick circuit for said directional relay and including a back contact of another track relay which a train shunts subsequent to passing through said track section in receding from the intersection, and means including a front contact of the directional relay to render the control relay ineffective to operate the signal when the receding train passes the location of said instrument.

8. In combination, a stretch of railway track intersected by a highway, a highway crossing signal located at the intersection, two track instruments capable of operation by a train and located one at each of two selected locations to one side of the intersection, a normally energized first relay governed by the track instrument nearer the intersection and effective to start operation of the signal when deenergized in response to the head end of a train reaching the location of that instrument, a normally deenergized time measuring means effective when energized a predetermined time to render said first relay ineffective to operate the signal, a normally energized second relay governed by the track instrument more remote from the intersection and effective to energize the time measuring means when deenergized in response to the head end of a train reaching the location of that instrument, and means controlled by a train upon reaching a fixed point between the track instrument nearer the intersection and the intersection to energize said first and second relays irrespective of the associated track instruments.

9. In combination, a stretch of railway track intersected by a highway, a highway crossing signal located at the intersection, two track instruments capable of operation by a train and located one at each of two selected locations to one side of the intersection, a first relay, a normally closed stick circuit for said first relay and including the track instrument nearer the intersection, operating means controlled by said relay and effective to operate said signal when said relay is deenergized, time measuring means operative when actuated a predetermined time interval to render said operating means ineffective to operate the signal, a second relay, a normally closed stick circuit for said second relay and including the track instrument more remote from the intersection, means controlled by said second relay when deenergized to actuate the time measuring means, two pick-up circuits one for each of said relays, and means controlled by a train upon reaching a fixed point between the track instrument nearer the intersection and the intersection to render the pick-up circuits each effective to energize the associated relay.
